Patented Jan. 14, 1975

234,094

COMBINED CAMERA AND FLASH UNIT

Karl-Heinz Lange, Bunde, Germany, assignor to Balda-Werke Photographische Geräte GmbH & Co. KG, Bunde, Germany

Filed Mar. 5, 1973, Ser. No. 337,978

Claims priority, application Germany Sept. 22, 1972

Term of patent 14 years

Int. Cl. D16—01

U.S. Cl. D61—1 B

FIG. 1 is a top plan view of a combined camera and flash unit showing my new design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a bottom plan view thereof;

FIG. 7 is a front perspective view thereof in the operative position shown on an enlarged scale, the flash unit having been omitted for ease of illustration;

FIG. 8 is an exploded rear perspective view of the camera and flash unit.

I claim:

The ornamental design for a combined camera and flash unit, as shown and described.
